CLAIM

We claim the ornamental design for an articulating mounting unit for audio/visual devices or the like, as shown and described.

DESCRIPTION

(62) Division of application No. 29/358,151, filed on Mar. 23, 2010, now Pat. No. Des. 623,177.

FIG. 1 is a top front perspective view of another embodiment of the articulating mounting unit for audio/visual devices or the like showing our new design;

(51) **LOC (9) Cl.** **14-03**

FIG. 2 is a bottom front perspective view of the articulating mounting unit for audio/visual devices or the like in FIG. 1;

(52) **U.S. Cl.** **D14/239**

FIG. 3 is a front elevational view of the articulating mounting unit for audio/visual devices or the like in FIG. 1;

(58) **Field of Classification Search** **D14/125-134,**

FIG. 4 is a right side elevational view of the articulating mounting unit for audio/visual devices or the like in FIG. 1;

FIG. 5 is a left side elevational view of the articulating mounting unit for audio/visual devices or the like in FIG. 1;

See application file for complete search history.

FIG. 6 is a top plan view of the articulating mounting unit for audio/visual devices or the like in FIG. 1;

FIG. 7 is a bottom plan view of the articulating mounting unit for audio/visual devices or the like in FIG. 1; and,

FIG. 8 is a rear elevational view of the articulating mounting unit for audio/visual devices or the like in FIG. 1.
